UNITED STATES PATENT OFFICE.

WALTER F. KASPER, OF FAIRMONT, MINNESOTA, ASSIGNOR TO FAIRMONT GAS ENGINE & RAILWAY MOTOR CAR CO., OF FAIRMONT, MINNESOTA, A CORPORATION.

ATTACHMENT FOR BINDERS.

1,275,699.

Specification of Letters Patent. Patented Aug. 13, 1918.

Application filed August 18, 1916. Serial No. 115,701.

To all whom it may concern:

Be it known that I, WALTER F. KASPER, a citizen of the United States, resident of Fairmont, county of Martin, State of Minnesota, have invented certain new and useful Improvements in Attachments for Binders, of which the following is a specification.

My invention relates to binders having a source of power mounted on the machine for 10 operating a portion of the mechanism, such as the aprons, reel, knotter, etc.

The primary object of my invention is to provide a means for supporting the source of power, such as a gas engine, which can 15 be applied to any style or type of binder, the attachment being adjustable and capable, therefore, of being fitted to raise or lower the engine base or adjust it forward or backward or laterally, as the connections to the 20 mechanism to be operated require.

A further object is to provide an engine supporting attachment which can be applied to a binder not originally constructed to be used with a motor.

25 Other objects of the invention will appear from the following detailed description.

The invention consists generally in various constructions and combinations, all as hereinafter described and particularly pointed 30 out in the claims.

In the accompanying drawings forming part of this specification,

Figure 1 is an elevation of a portion of a binder, illustrating the application of my 35 invention thereto,

Fig. 2 is a detail view, showing the preferred means for securing the attachment to the frame of the binder,

Fig. 3 is a detail view of the device de- 40 tached from the binder.

In the drawing, 2 represents the frame of the binder, having the usual U-shaped support 3 secured thereon upon which the tool box and the driver's seat (not shown) are 45 mounted in any suitable manner. 4 represents brackets having holes 5 therein to receive U-shaped bolts 6 which clasp the bars of the frame, as indicated in Fig. 2, and are adjustable vertically thereon by means 50 of said holes and are inwardly and upwardly inclined. The upper ends of these brackets have clamps 7 for a shaft 8, and clamps 9 and 10 are secured to the shaft and

are connected to the lower ends of rods 11 and 12, the upper ends of which are secured 55 to a bar 13 and a brace 14 of the binder frame. A brace 15 connects the clamp 16 on the shaft 8 with the U-shaped support 3, as shown in Fig. 1. These braces and rods are adjustable in their clamps on the shaft 8 60 and permit the raising and lowering of the shaft to vary the elevation of the engine supporting platform thereon. On this shaft 8 I provide a platform 17 having depending brackets 18 which straddle the shaft 8 and 65 are secured thereto by means of bolts 19. This base 17 has a flat upper surface and is provided with slots 20 to receive bolts 21 which secure the engine base 22 to the base 17, providing a firm, substantial support for 70 the motor and at the same time permitting its position to be changed through the adjustment of the connections of the shaft 8 with the frame of the machine.

It will be noted that the shaft is capable 75 of rotary adjustment in its bearings and consequently the motor may be tilted to level it on the machine or change the position of its drive shaft with respect to the mechanism to be operated.

This attachment is of such construction 80 that it can be applied to any style or type of binder without change in construction, the parts are adjustable, so that the base for the motor can be raised or lowered until the de- 85 sired elevation is reached, and the proper connections can be made to the parts operated from the motor. The form of the supporting brackets may be varied, and in various ways the details of construction can be 90 modified and still be within the scope of my invention.

I claim as my invention:

1. The combination, with a binder frame, of a shaft mounted for vertical adjustment 95 thereon, a base mounted on said shaft and having an upper surface forming a support for a motor, and braces connecting said shaft with said frame.

2. The combination, with a binder frame, 100 of a shaft mounted for vertical adjustment thereon, and a motor base mounted for rotary adjustment on said shaft and having an upper surface adapted to receive a motor.

3. The combination, with a binder frame, 105 of brackets mounted thereon, boxes carried

by said brackets, a shaft having bearings in
said boxes and mounted for longitudinal or
rotary adjustment therein, braces connecting
said shaft with said frame, and a motor base
5 mounted on said shaft and having an upper
surface adapted to receive a motor.

In witness whereof, I have hereunto set
my hand this 25th day of July, 1916.

WALTER F. KASPER.
